UNITED STATES PATENT OFFICE.

CHARLES P. HANSEN, OF EVAN, MINNESOTA.

DESIGN FOR A RADIO DIAL ESCUTCHEON PLATE.

Application filed March 5, 1928. Serial No. 25,674. Term of patent 14 years.

To all whom it may concern:

Be it known that I, CHARLES P. HANSEN, a citizen of the United States, residing at Evan, in the county of Brown and State of Minnesota, have invented a new, original, and ornamental Design for Radiodial Escutcheon Plate, of which the following is a specification, reference being had to the ac-

companying drawing, forming part thereof. Figure 1 is a front elevation, and Figure 2 is an end elevation of my design.

I claim:

The ornamental design for a radiodial escutcheon plate, as shown.

CHARLES P. HANSEN.
